UNITED STATES PATENT OFFICE.

GEORGE F. PATTERSON, OF BALTIMORE, MARYLAND.

FEED-WATER REGULATOR.

1,266,619.

Specification of Letters Patent. Patented May 21, 1918.

Application filed May 4, 1917. Serial No. 166,285.

To all whom it may concern:

Be it known that I, GEORGE F. PATTERSON, a citizen of the United States, residing at Baltimore, in the State of Maryland, have 5 invented certain new and useful Improvements in Feed-Water Regulators, of which the following is a specification.

This invention relates to improvements in feed water regulators and has for its 10 object to provide an improved construction of device for regulating the feed of water to boilers that will operate promptly to feed and then cut off the water supply when the water level in the boiler has first fallen and 15 then become replenished, so that the water level in the boiler may, as near as possible, be maintained at a predetermined level.

Another object of the invention is to provide an improved water regulator combining 20 a motor to operate a pump or water supply device; a pressure generator to generate a pressure for the pump or supply device and a controller to govern the operation of the pressure generator and itself 25 operated by the pressure of the generator which it controls.

The accompanying drawing illustrates the invention wherein the single view shows the improved device, partly in side elevation 30 and partly in sectional elevation.

The present invention is an improvement over the device shown and described in my prior Patent Number 1,002,080, granted 35 August 29th, 1911,—particularly in that I now employ a pressure-operated controller which governs the operation of the pressure generator in such a way as to render the operation quicker and even more delicate than heretofore.

Referring to the drawing by numerals, 40 1, designates a water column; 2, a steam pipe that connects the boiler, not shown, with the upper part of the water column and 3, a pipe which connects the water column 45 with the boiler below the water line so that the water column will have a water level on a line 4, with the level of the water in the boiler. A glass tube 5, is provided on the water column to show the actual water 50 level in the boiler and water column.

A pressure generator casing 6, is provided which has a lower chamber 7, and an upper chamber 8, that are separated by means of a partition 9.

55 A steam pipe 10, extends from the water column at a point above the water line 4,

and enters one end of the lower chamber 7, of the pressure generator. At this steam entrance end, the lower chamber 7, of the pressure generator is provided with a port 60 having a beveled valve seat 11, and a valve 12, having the form of a stem extends horizontally in the lower chamber 7, and has a beveled end 13, to fit the seat 11. This valve stem 12, extends from one end of the 65 chamber 7, and through the casing 6, so that it may be actuated by means that will presently be explained.

A pipe 14, extends from the water column at a point below the water line and has a 70 branch 15 that also enters the lower chamber 7, of the pressure generator. A branch pipe 16, is provided to connect the pipes 10 and 14 and thereby enable a circulation to and from the water column and to also afford 75 a circulation from the chamber 7, by means of said pipes 14, 15 and 16.

The generator casing 6, has a bracket 17, extending horizontally from one end and said bracket is provided with stationary 80 cross-bars 18 and 19 respectively. A head 20, having a threaded plug 21, screws into the bar 18, and the valve stem 12, extends freely therethrough. The outer end of the valve stem carries a head 22, which seats 85 against the cross-bar 19, of the bracket and a spring 23, encircles the stem and is compressed between the heads 20, and 22, to exert a constant pressure on the head 22, and thereby tend to keep the stem pressed 90 outwardly with its inner end drawn away from the valve seat 11.

The outer end of the bracket 17, carries a chambered casing 24, with a diaphragm 25, at one side thereof and a short stem 26, 95 is interposed between one side of this diaphragm and the head 22, on the outer end of the stem, so that movement of the diaphragm, in a direction toward the head 22, will impart a horizontal movement to the 100 stem and thereby move its inner end against the valve seat 11, to close the port from pipe 10, to the lower chamber 7, of the pressure generator.

A pipe 27, enters the upper chamber 8, 105 of the pressure generator and has its upper end communicating with the lower end of a receptacle 28, while another pipe 29, also enters said upper chamber and has a branch 30, that extends to and enters the casing 24, 110 at the outer side of diaphragm 25. A pipe 31, extends from the upper side of recepta-

cle 28, and communicates with pipe 29, so that a circulation may take place from upper chamber 8, by pipes 27, 29 and 31, with the receptacle 28. The receptacle 28, pipes 27 and 29, and upper chamber 8, are all provided with water, and a gage pipe 32, and gage 33, are provided to indicate the pressure that is generated in said receptacle and chamber.

10 In carrying out my invention I also make use of a motor or power mechanism whose function is to set in motion means that will supply water to the boiler. This device may be coupled with a valve in a steam pipe to 15 open the latter and set in motion a pump, or the valve may be located in a water supply pipe so that when actuated, it will allow water to pass to the boiler.

The form of motor or power device may 20 vary, but in the present instance, I employ a bracket, 34, having a recess 35, at one side so that a diaphragm 36, may be seated against said side and over said recess. A disk 37, is provided at the outer side of the 25 diaphragm, and a stem 38, has one end seated against said disk and extends laterally therefrom. A cross-bar 39, engages the outer end of the stem so that when the diaphragm is bulged outwardly by pressure admitted to the recess 35, the stem and cross-bar both will be given a limited outward movement. The opposite ends of the cross-bar are provided with link bars 40, which latter have bearing in guide brackets 41, at 35 the side of the bracket 34. The two link bars connect with the opposite ends of a cross-bar 42, which latter passes through a slotted head 43, and said head connects with a valve-stem 44, which latter enters a valve 45, and engages a valve 46, therein. Pipes 47, and 48, serve to provide a supply of steam for a pump or to convey water directly to the boiler as desired and the valve 46, simply serves to control the passage of 45 either the steam or the water through said pipes.

The head 43, has one side seated against one end of a stem 49, and another and movable head 50, receives the other end of said 50 stem. A coiled spring 51, has one end seated against the movable head 50, and its other end engaging an adjustably fixed head 52, at the side of the recessed portion of the bracket 34, so that said spring may exert a 55 yielding pressure on the stem 49, head 43, links 40, stem 38, and the diaphragm 36, as will readily be seen.

A pipe 53, branches from pipes 29 and 31, of the pressure generator and communicates 60 with the recess 35, at the side of the diaphragm 36.

Obviously the motor or power device just described may be located at a place remote from the boiler or pressure generator and 65 the pipe 53, will simply be of sufficient

length to make the connection above described.

In operation, and presuming the boiler to have the desired water level, the valve stem 12, will be withdrawn from the beveled 70 seat 11, and water from the boiler will therefore enter the lower chamber 7, of the pressure generator. When the water in the boiler falls, however, steam will enter said lower chamber 7, by pipe 10, and this steam 75 will heat the partition 9, and the water in the upper chamber 8, and thereby produce a pressure in the upper chamber 8, and the pipes connected therewith. As pipe 53, conveys this generated pressure to the recess 80 35, of the motor or power device such pressure will act on diaphragm 36, and spring the same outwardly, thereby moving stem 38; cross-bar 39; links 40; valve stem 44; and valve 46, in a direction to open communication between pipes 47 and 48, so that steam may pass through to operate a water pump or water may pass to the boiler. The pressure in generator chamber 8, will continue to rise, say until fifteen pounds is reached, 85 whereupon that pressure which is conveyed by branch pipe 30, to one side of diaphragm 25, will bulge the latter and push valve stem 12, to the seat 11, thereby closing off the steam supply to the lower chamber 7. 90

The supply of water to the boiler will continue until the water level again reaches line 4, whereupon the water will back up in pipe 15, into the lower chamber 7, and quickly lower the temperature in said chamber and 100 also cause the pressure in chamber 8, to drop and release the diaphragm 25, so that valve stem 12, will again be opened, and the reduction in temperature is effected so fast that pressure in pipe 53, will drop sufficiently to 105 allow diaphragm 36, to assume its normal position and thereby effect a closing of supply valve 46.

It is to be understood that the motor diaphragm 36, operates on a lower pressure 110 than the pressure generator diaphragm 25, consequently the former will operate to feed water before the latter operates, but the latter serves a very useful purpose in that it promptly cuts off the steam when the pressure in the upper chamber 8, has reached a 115 point where cooling may begin, it being determined in practice that by the time the pressure is reduced sufficiently to enable the diaphragm 36, to return, sufficient water will 120 have been supplied to the boiler to reach the desired level.

The pressure generator diaphragm as now employed therefore materially aids in the prompt action of the devices to feed and 125 then cut off the water supply.

Having described my invention what I claim is,—

1. In a feed water regulator for boilers the combination with a pressure generator 130

having a pressure chamber and another chamber in heat transferring relation with the pressure chamber and said other chamber having connections from both the water and steam spaces of a boiler, of a valve to control the steam connection to said latter chamber; means controlled by the pressure in the pressure chamber for operating said valve; valve means for controlling the passage of feed water to the boiler and means operated by pressure generated in said pressure chamber for actuating said valve means.

2. In a feed water regulator for boilers the combination with a pressure generator having a chamber, of means for heating said chamber; a valve for controlling said heating means; means controlled by the pressure in the chamber for operating the valve; means for controlling the passage of feed water to the boiler; pressure operated means for controlling said latter means and connections between the chamber of the pressure generator and said pressure operated means whereby the latter may be operated.

3. In a feed water regulator for boilers the combination with a generator having a pressure chamber, of means for heating said chamber; a valve for controlling said heating means; a casing having a chamber with a diaphragm therein said diaphragm having connection with said valve; connections between the pressure chamber and the casing chamber; means for controlling the passage of water to the boiler; pressure operated means for controlling said latter means and connections between the pressure chamber of the generator and the said pressure operated means.

4. In a water feed regulator for boilers

the combination with a generator having a pressure chamber, of means for heating said chamber; a valve for controlling said heating means; a casing having a chamber with a diaphragm therein said diaphragm having connection with said valve; connections between the pressure chamber and the casing chamber; means for controlling the passage of water to the boiler; a casing having a diaphragm therein said latter diaphragm having connection with the means that controls the said water passage and connections between the pressure chamber of the generator and the said latter diaphragm.

5. In a water feed regulator for boilers the combination with a water column, of a pressure generator having two chambers; connections between the upper and lower portions of the water column and one of the pressure generator chambers; a valve movable in said latter chamber to cut off communication through the connection from the upper portion of the water column; a casing having a chamber with a diaphragm therein said diaphragm being connected to the valve; means for conveying the pressure in the other chamber of the generator to one side of the diaphragm in the casing chamber; means for controlling the passage of water to the boiler and connection between said latter means and the said other chamber of the pressure generator.

In testimony whereof I affix my signature in presence of two witnesses.
